UNITED STATES PATENT OFFICE.

EUGÈNE SOLOMON MANNY, OF MONTREAL, QUEBEC, CANADA.

PIPE ATTACHMENT FOR TUBULAR FURNACES.

1,240,994.

Specification of Letters Patent. Patented Sept. 25, 1917.

Application filed February 12, 1917. Serial No. 148,294.

To all whom it may concern:

Be it known that I, EUGÈNE SOLOMON MANNY, a subject of the King of Great Britain, and residing at 27 Côté street, in the city of Montreal, in the Province of Quebec, in the Dominion of Canada, have invented certain new and useful Improvements in Pipe Attachments for Tubular Furnaces; and I do hereby declare that the following is a full, clear, and exact description of the same.

The invention relates to improvements in a "pipe attachment for furnaces, water heaters, or the like", of the type of tubular furnaces having outer circulating tubes and inner tubes.

The object of the invention is to provide an attachment which will enable the inner tube to be properly supported within the outer tube and at the same time will not obstruct the expansion caused by the heat.

A further object of the invention is to provide an attachment, cheap of construction and easy to adapt, which will considerably reduce the difficulty encountered in securing the inner tube in this class of furnace.

In the drawings, Figure 1 is a sectional view through a furnace of the type mentioned, showing the disposition of the tubes.

Fig. 2 is an enlarged longitudinal section through one of the outer tubes, being shown secured to one of the water legs, the inner tube being shown in position with the attachment.

Fig. 3 is a perspective view of the inner tube support at one end.

Fig. 4 is a cross section on line A—A of Fig. 2, and

Fig. 5 is a cross section on line B—B of Fig. 2.

Like numerals of reference indicate corresponding parts in each figure.

In the drawings, 1 indicates the front wall of a furnace, 2 the rear wall, and 3 the side walls. The furnace casing in the rear is preferably divided into two vertical sections by the water legs 4 and 5. 6 are the outer circulating tubes having their front ends closed and their rear ends internally threaded at 7.

Each of the outer circulating tubes is provided with longitudinal ribs 8 around its circumference at its rear end and with a square or nut-shaped head 9 at its front end. 10 are legs or supports, preferably

three in number, provided within said outer tube at its front end.

The water leg 4 is provided with a series of threaded openings 11 and the water leg 5 is provided with corresponding circular openings 12 which are in alinement with the openings 11 in said water leg 4, but smaller in diameter. 13 is a collar or nipple, which is screwed into the threaded opening 11 into the threaded end 7 of the outer circulating tube 6. The said nipple 13 is provided at one end with outwardly projecting arms 14 which terminate at the outer end thereof, in an integral collar 15, the latter being disposed in alinement with the circular opening 12 in the water leg 5.

16 is an inner circulating tube, free within said outer tube 6, and supported at its front or outer end by the supports or lugs 10, the inner end of said tube being preferably smaller in diameter on its outer circumference so as to enable it to be inserted through the collar 15 and through the circular opening 12 in the leg 5, thus establishing a water circulation between the two compartments.

17 is a set screw provided on said collar 13 and rigidly securing said inner tube 16 in position.

It will readily be seen that the inner circulating tube will be well supported within the outer tube without, in any way, preventing the full expansion of the said tube. Further, it may be stated that it was found advisable that the inner tube be unthreaded at both ends in order to have full and equal expansion: therefore, the device above disclosed is thought to have a great advantage over all the means now employed in securing the inner tube.

A further advantage of this device is that the inner tube can readily be secured within the outer tube and both placed in position merely by screwing the nipple 13 in the leg 4, thus saving considerable time in fitting the furnace with its tubes.

The square or nut-shaped head 9 on the front end of the outer tube permits the use of a wrench in putting said tube in place, while the ribs 8 may be used in screwing the nipple 13 on the threaded end 7 of the outer tube 6.

What I claim is:

In a furnace, the combination, with spaced outer and inner water legs formed with coaxial openings, the opening in the outer

water leg being threaded, and the opening in the inner water leg being plain and having a smaller diameter than the first-named opening; of an outer water-circulating tube 5 closed at one end and having its other end disposed in registration with the opening in said outer water leg and internally threaded; a nipple threaded through the said opening in the outer water leg into the 10 second-named end of said tube, said nipple being formed with a plurality of spaced arms which project into the space between the water legs and are connected at their extremities by an annular supporting member 15 of appreciably smaller diameter than said tube; an open-ended inner water-circulating tube disposed within the outer tube and pro-

jecting at one end through said annular supporting member and the plain opening in the inner water leg into the space between 20 the latter and the back wall of the furnace, the other end of said inner tube terminating short of the closed end of the outer tube; and a plurality of supporting members arranged within said outer tube and grouped 25 around the said other end of inner tube, whereby said inner tube is maintained in spaced relation within said outer tube.

Signed at Montreal, Quebec, Canada, this fourth day of January, 1917.

EUGÈNE SOLOMON MANNY.
